UNITED STATES PATENT OFFICE.

GEORGE STEINGRUBER, OF HAZLEHURST, MISSISSIPPI.

HINGE.

1,073,537.

Specification of Letters Patent.

Patented Sept. 16, 1913.

Application filed April 26, 1913. Serial No. 763,819.

To all whom it may concern:

Be it known that I, GEORGE STEINGRUBER, a citizen of the United States, residing at Hazlehurst, in the county of Copiah and 5 State of Mississippi, have invented certain new and useful Improvements in Hinges, of which the following is a specification.

The object of the present invention is to provide a novel form of hinge adapted particularly to join together two members such as the sections of a foldable table leaf so as to permit folding of said sections or the movement of one section through a plane of one hundred and eighty degrees with respect to the other section.

In carrying out the invention it is contemplated to provide a hinge consisting of two attaching members each of which has formed therein a socket to receive one end 10 of a connecting link, said socket terminating in shoulders adapted to limit the opening and closing movements of the hinge or of the link connecting the hinge members aforesaid.

One of the principal features of my invention is the provision of a hinge of the above nature which is susceptible of being set into the adjoining edges of a foldable member instead of connecting said members 20 at their outer edge portions, whereby said foldable member in their connected condition may be passed through the machinery for planing its top surface as well as the edge portions in which the hinge members 30 are set.

With the above and other objects in view, this invention consists in the construction, combination and arrangement of parts all as hereinafter more fully described, claimed 40 and illustrated in the accompanying drawings, wherein:

Figure 1 is a view partially in section and showing the application of a hinge constructed in accordance with my invention, a portion being broken away to show more clearly the arrangement of the connecting link for the hinge members. Fig. 2 is a fragmentary view of the contiguous edge portions of the foldable member to which 45 my hinge is attached, said hinge being in closed position. Fig. 3 is a plan view showing the hinge in open position. Fig. 4 is a longitudinal sectional view taken about on the line 4—4 of Fig. 1. Figs. 5, 6 and 7 55 are detail views of the side plate, interme-

diate plate and connecting link respectively used in the construction of my hinge.

Throughout the following detail description, and on the several figures of the drawings, similar parts are referred to by like 60 reference characters.

Specifically describing my invention and referring to the drawings the numerals 1 and 2 represent the sections of a foldable member to be connected by means of my 65 hinge invention. These sections for the purpose of this description will be termed the sections of a table leaf, in the abutting edge portions of which one or more of these hinges may be inset. The hinge constituting 70 my invention consists of a pair of attaching members 3 of identical shape and construction, which members are connected together by means of a link 4. Each of the members 3 comprises an internal socket in 75 which the link 4 is adapted to work as will now be set forth.

As a matter of convenience in the manufacture of my invention, each of the members 3 is formed of a pair of outer plates 5, 80 shown most clearly in Fig. 5 of the drawings, which plates are bent at right angles at their upper portion to form a wing 6, the wings of the outer plates of each member 3 being bent in opposite directions as shown 85 in Fig. 3. Between the outer plates 5 is disposed an inner or intermediate plate 7 as shown in Fig. 6 of the drawing, said plate being cut away at one of its lower corners as designated by the numeral 8, the 90 cut-away portion being of semicircular shape.

The outer plates 5 and the inner plate 7 just mentioned are fastened together by means of rivets or other like members 9 95 passing through openings 9' in said plates and the link 4 is then pivotally mounted upon a pin 4' so as to pivotally connect said link with the hinge member 3, it being understood that the link is connected at each 100 end in the manner above described to join together the two attaching members 3 of my hinge construction. The cut away portion 8 in the intermediate plate 7 of each hinge member forms a socket in which the link 4 105 moves and this socket or cut away portion terminates in an upper shoulder *a* and a lower shoulder *b* which shoulders limit the upward and downward movement of the link 4. The outer plates 5 at the corners 110

adjacent the socket 8 are cut away diagonally as indicated by the numeral 10 so as to permit the movement of one hinge member 3 with respect to the other as the hinge 5 is moved from an open to a closed position. Each of the wings 6 of the hinge members 3 is provided with an opening 6' so that the hinges may be secured in position by means of screws 6''.

10 It will be understood that the leaf members or sections 1 and 2 in applying my hinge are first provided with the necessary openings or holes in which the body portion of each hinge member 3 is adapted to be seated, the wings 6 preferably lying in a lower plane than the top of the sections 1 and 2 which may then be run through a planing machine and smoothed in the usual manner. The foldable leaf may then be 15 passed through a machine for properly jointing the abutting edges of the leaves and all this may be done after the hinge has been applied in position as above described, thus assuring the proper adjustment of the 20 leaf sections 1 and 2 with respect to each other. Any number of these hinges may be inserted on the abutting edge portions of the leaf sections as will be obvious, the hinge construction making a very strong and durable connecting means for this purpose. 25 The coöperation of the link 4 with the ter-

minals *a* and *b* of the socket 8 formed in each hinge will be clearly understood by reference to Fig. 1. That is to say, the true alinement of the edge portions of the sections of the leaf is determined by the abutment of the link member 4 with the lower shoulders *b* of the sockets 8, while the true alinement of the upper surface of said sections is determined by the abutment of the 35 link 4 with the upper shoulders *a*.

Having thus described the invention, what is claimed as new is:

A hinge comprising a pair of attaching members each consisting of a pair of outer 45 plates having opposing wing portions bent at angles to said plate and a plate disposed intermediate the outer plates, said last mentioned plate being cut away so as to form an internal socket, the terminals of said cut away portion forming abutment shoulders, and a rectangular link connected to said members so as to pivotally move in said cut away portions, the terminal shoulders of 50 said cut-away portion limiting movements 55 of the link in opposite directions.

In testimony whereof I affix my signature in presence of two witnesses.

G. STEINGRUBER.
